UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

DOUBLE-DRUM HOIST.

Application filed September 16, 1925. Serial No. 56,568.

This invention relates to hoists, but more particularly to hoists of the double drum type in which either drum may be driven from a common driving shaft.

5 The objects of the invention are to employ fluid actuated means for automatically connecting one or the other of the drums with a common source of power to be rotated in accordance with the direction of rotation of 10 the power element, and to construct a rugged, compact and efficient hoist in which either of the drums and their associated elements may be readily assembled and disassembled without disturbing the assembly of 15 the other drum.

Other objects will be in part obvious and in part pointed out hereinafter.

The invention consists of the combinations 20 of elements, features of construction and arrangement of parts having the general mode of operation substantially as herein-after described and more particularly pointed out in the appended claims and illustrated in the accompanying drawings, in 25 which—

Figure 1 is a longitudinal view in elevation and partly in section of a double drum hoist constructed in accordance with the practice of the invention,

20 Figure 2 is a view through Figure 1 taken on the line 2—2 looking in the direction of the arrows, and

Figure 3 is a top plan view taken through Figure 2 on the line 3—3 looking in the direction of the arrows, illustrating the main driver and opposed drum drivers.

Referring to the drawings, A indicates a base plate having an upwardly extending semi-circular frame B to which is bolted or 40 otherwise secured a top frame C. The frame B and the top frame C are provided with flanges D and E at their outer faces or ends. The flange D provides a support for a side plate F which may be secured to said flange 45 by means of bolts. Likewise the flange E forms a support for a side plate G. The side plate G forms a cover for a portion of one side of the hoist and has formed integrally therewith a gear casing H. The 50 plates F and G in this instance also serve as a support for a hollow main shaft J extending longitudinally of the hoist and supported near its ends with anti-friction bearings K.

55 A haulage drum L and a tail rope drum O

are mounted loosely upon the main shaft J and carry on their inner faces opposed drum drivers P and Q respectively. The drum drivers P and Q are in this instance formed integrally with the drums L and O and are 60 preferably provided with oppositely extending teeth adapted to interlock with corresponding teeth carried by a main driver R located between the drums L and O and mounted slidably on the main shaft J. Keys 65 S cooperating with the main driver R and the main shaft J to prevent rotation of the main driver with respect to said main shaft are preferably held stationary in the main shaft J and fit loosely in the main driver R. 70

Power for rotating the main shaft is supplied by a motor T, in this instance secured or mounted on the end of the gear casing H below the longitudinal axis of the drums and having a side plate U. The motor T may 75 be of the flat piston type, sometimes termed the "Dake motor", although any other suitable type of reversible motor of compact construction may be used. A side cover plate V is provided for the motor T and has formed 80 integrally therewith an exhaust chamber W to receive the exhaust from the motor and from whence the exhaust may pass to the atmosphere through a connection W'. Pressure fluid for actuating the hoist may be 85 supplied directly to a throttle valve X arranged rotatably in the cover plate V and which valve controls the admission of pressure fluid to the motor together with the reversal of said motor. A throttle lever Y secured to the valve X provides a convenient means for manipulating said valve.

A crank shaft Z having a crank pin b whereby said shaft is connected with the motor is provided with anti-friction bearings c and d arranged in the plates G and U respectively and carries a pinion e keyed to said shaft which meshes with a gear f carried by a driving shaft g. The driving shaft g extends longitudinally of the hoist 100 and preferably beneath the drums L and O and is encased by a suitable housing h which is supported at one end by the plate F and at its other end by the gear casing H. An anti-friction bearing j arranged in one end 105 of the housing h supports one end of the shaft g and the other end of the shaft is provided with an anti-friction bearing k supported by an end cover o which is secured to the plate F. In addition to form- 110

ing a support for one end of the shaft *h*, the cover *o* also serves as a gear casing.

A pinion *p* keyed to the end of the shaft *h* which extends into the cover *o* meshes with a gear *q* keyed to the main shaft *J*. In this instance the gear *q* is held against longitudinal movement on the shaft *J* by a suitable nut *r*. A similar nut *r* is screwed on the opposite end of the main shaft *J* and with the other nut *r* prevents longitudinal movement of the shaft *J* and the elements mounted thereon. By means of the train of gearing described, power from the motor will be transmitted to the main shaft *J* for rotating said shaft and the crank shaft *Z* is in this instance provided with a member *s* keyed thereto for counterbalancing the motor *T*.

Separate fluid actuated means are provided for moving the main driver into engagement with one or the other of the opposed drivers carried by the drums. To this end a cylinder *t* is formed integrally with the cover plate *V* and is preferably located coaxially with the main shaft *J*. The cylinder *t* has a cover plate *u* and is provided with a reciprocatory piston *v*. A piston rod *w*, removably secured to the piston *v* in any suitable manner, extends through one end of the main shaft *J* and is connected at one end with a cross head *x* arranged slidably in the main shaft *J* and which supports an anti-friction bearing *y* for the piston rod *w*. The piston rod *w* is preferably held to the bearing *y* by means of a screw *z* extending through said bearing and forming a trunnion for the inner member of said bearing. The end of the cross head *x* is preferably screw threaded as at 2 to receive a correspondingly screw threaded collar or nut *3* for holding the bearing *y* within the cross head *x*. The cross head *x* is provided with a transverse bore 4 to receive a bolt 5 which extends through slots 6 on opposite sides of the main shaft *J* and engages at its ends the main driver *R*. The bolt 5 is preferably held against endwise movement by a nut 7 screwed on one end thereof. The slots 6 may be of any suitable length to permit sliding of the bolt 5 therein, but are preferably of a length to permit the head of the bolt 5 to pass over the inner faces of either drum in case it be desired to remove said bolt.

From the foregoing description it will be seen that the main driver *R* and the cross head *x* are slidably longitudinally with respect to the main shaft *J* but are held against rotation with respect thereto.

The admission of pressure fluid to the cylinder *t* is in this instance also controlled by the throttle valve *X*. The throttle valve *X* has a pair of ports 8 and 9 adapted to register with passages 10

and 11 respectively leading to the ends of the cylinder *t*. An exhaust port 12 is suitably located to provide communication between the atmosphere and a groove 13 formed on the valve. The groove 13 is so formed on the valve that when said valve is rotated from one limiting position to the other, said groove will register with one or the other of the passages 10 and 11 and with the exhaust passage 12 for the purpose of exhausting pressure fluid from the cylinder ends. As before stated, the valve *X* also controls the admission of pressure fluid to the motor, and the ports leading to the motor as well as the ports 8 and 9 are so arranged with respect to each other that pressure fluid is simultaneously supplied to the motor and to one or the other of the cylinder ends depending upon the direction of rotation of the valve *X*.

Braking means are provided for holding the drums against rotation after the main driver has been disconnected from the drum drivers. To this end a flange 14 is formed on adjacent faces of each drum to receive brake bands 15 which partly encircle the flanges 14. The bands 15 may be manipulated by any suitable means such as for instance a lever 16, but since such brakes are usually provided in hoists of this type and inasmuch as their functioning and operation are well known, further description thereof is considered unnecessary.

In the operation of the hoist, assuming that it be desired to rotate the haulage drum *L* in a clockwise direction, the throttle valve *X* may be rotated to place the port 8 of the valve in registration with the port 10 to admit pressure fluid into the front end of the cylinder *t*. In this way, the main driver *R* will be moved into engagement with the drum drivers *P* and thus hold the drum stationary with respect to the main shaft *J* and cause said drum to rotate therewith. Upon reversal of the throttle valve *X*, pressure fluid from the front end of the cylinder *t* will pass through the port 10 and groove 13 to the atmosphere through the exhaust port 12. Continued rotation of the valve *X* in the described direction will place the port 9 in registration with the passage 11 for admitting pressure fluid to the rear end of the cylinder *t* for moving the main driver *R* into engagement with the drum driver *Q* carried by the drum *O*. Reversal of the valve *X* will also cause reversal of the motor so that the drum *O* will rotate in a counter-clockwise direction.

I claim:

1. In a double drum hoist, the combination of a base plate having an upwardly extending semi-circular frame, a top semi-circular frame secured thereto, both frames having meeting flanges at their outer ends, openings in the sides of said frames for

haulage and tail ropes, a hollow drum shaft extending longitudinally through said frames, a pair of drums rotatable in the frames relatively to said shaft, side plates secured to the flanges of said frames, one side plate having a gear casing, a motor secured against said gear casing below the longitudinal axis of said drums, opposed drum drivers on the opposite inner faces 10 of said drums, a main driver and clutch mechanism mounted on the drum shaft between the drums, and fluid actuated means located above the motor having an actuating rod extending through the hollow 15 drum shaft, for controlling said clutch mechanism, whereby one drum or the other may be clutched to the drum shaft.

2. In a double drum hoist, the combination of a base plate having an upwardly extending semi-circular frame, a top semi-circular frame secured thereto, both frames 20 having meeting flanges at their outer ends,

openings in the sides of said frames for haulage and tail ropes, a hollow drum shaft extending longitudinally through said 25 frames, a pair of drums rotatable in the frames relatively to said shaft, side plates secured to the flanges of said frames, one side plate having a gear casing, a motor secured against said gear casing below the 30 longitudinal axis of said drums, opposed drum drivers on the opposite inner faces of said drums, a main driver and clutch mechanism mounted on the drum shaft between the drums, a cylinder and fluid actuated piston mounted above the motor in line with the drum shaft, and a piston rod extending 35 through the drum shaft and operatively connected to control said clutch mechanism, whereby one drum or the other may be 40 clutched to the drum shaft.

In testimony whereof I have signed this specification.

CHARLES C. HANSEN.
